UNITED STATES PATENT OFFICE.

BERNHARD POL, OF BANGOR, MAINE.

DESIGN FOR A SPOON, &c.

SPECIFICATION forming part of Design No. 20,961, dated July 21, 1891.

Application filed April 28, 1891. Serial No. 390,840. Term of patent 7 years.

To all whom it may concern:

Be it known that I, BERNHARD POL, a citizen of the United States, residing at Bangor, in the county of Penobscot and State of Maine, have invented and produced a new and original Design for Spoons, &c., of which the following is a specification, reference being had to the accompanying drawing, forming part thereof.

10 The accompanying drawing represents my design.

The features of my design are the representation of the bust of some public or noted character in history or local affairs, a facsimile of the signature of such person, and the seal of the State or place with which the person is or has been identified.

15 The handle B of the spoon is carved or otherwise formed to represent flowers or scroll-work, and at or near the outer end of the

handle a panel C is formed, said panel being also surrounded with some fanciful scroll-work or other ornamental finish. In this panel is engraved the fac-simile autograph. The extremity of the handle is made in the 25 form of a bust, and in the bowl, if the design be applied to a spoon, the seal is represented. The fac-simile autograph is not an original feature of my design, and hence I make no claim to it.

20 My design for a handle may also be applied to the handles of other table articles, such as knives and forks.

What I claim is—

25 The design for a spoon, as herein shown and described.

BERNHARD POL.
